MATERIAL DRYING METHOD

Charles W. Gordon, Glen Ellyn, Ill., assignor to
Combustion Engineering Company, Inc., New
York, N. Y.

Application April 24, 1941, Serial No. 390,063

3 Claims. (Cl. 34—10)

This invention relates to drying moisture laden materials and particularly to an improved method for drying sewage sludge so as to control the particle size of the product.

In drying sewage sludge by a "flash drying" process such as disclosed in the U. S. Patent No. 2,157,775 granted May 9, 1939, to Alfred R. Smith, the dried product has consisted of fine sized particles suitable for use as fuel in the furnace from which were taken the hot gases for the drying process. The fineness of the dried product while desirable for burning it in suspension is disadvantageous for handling and for storage because of the fire risk. However, there is a market for a coarser dried product suitable for use as fertilizer. It is an object of this invention to control the operation of a "flash drying system" so that the dried product delivered from the system may be of predetermined particle sizes.

In the accompanying drawing the single figure is a diagrammatic view of a flash drying system suited to carrying out the invention.

Raw wet material is fed into a hopper 10 and delivered to a mixer 12 having a mixing screw 14. Previously dried material, known as "dry return," is fed to the mixer through a pipe 16 and the raw material and dry return become intimately mixed during their progress through the mixing chamber so that by the time the mixture reaches the outlet 18 it consists of a mass of small discrete particles. This mass of separate particles is fed through outlet 18 to a drying tower 20 where it enters a current of hot gases which in the particular form shown are the products of combustion from a furnace 22. The current of hot gases causes a portion of the moisture in the particles to flash into steam.

The evaporating or drying process is continued in the flash drier 24, in which there is a rotor driven by motor 26, the rotor being equipped with bars to create a turbulence of gases and particles during the drying process. The rotor shaft 31 carries a disk 33 on which are mounted bars 34 supported at their opposite ends by rings 35. Alternating with the rotating bars 34 are stationary bars 36 which are fastened to wall 37 at one end to supporting rings 38 at the other. If greater agitation is required, these stationary bars may be made to rotate in the opposite direction to bars 34. Material to be dried enters the flash drier from tower 20 through the central opening 40. After being thoroughly agitated within the current of hot gases while passing through the flash drier, the mixture of gases, evaporated moisture and dried particles leaves the drier 24 and passes

5 through duct 42 to the exhaust fan 44 which forces the current of gases and solids in suspension to the separator 46. The gases leave the separator at 48, the particles separated being delivered at the bottom of the separator to pipe 50. Pipe 50 divides into the two branches 51 and 16, the latter of which delivers dried material to the mixer 12 as described above. The finished product removed from the system passes through pipe 51. The damper 52 is employed to alternately completely close one of the two branches, leaving the second one open and then completely close the second branch, leaving the first branch open. Any changes in the ratio of distribution between the two branches may be made by adjusting the length of time which one of the branches is open relatively to the length of time the other is open. For example, if it is found that for proper operation two thirds of the dried material should be returned and one third discharged, the passage 16 is kept open two units of time for each unit of time that the branch 51 is open.

20 The drying system described above is essentially that of the Smith patent. Utilizing drying apparatus of this type I have found that by regulating the moisture content of the mixture of material delivered to drier 24, varying the speed of operation of the mixer 12 and drier 24, and controlling the temperature in the cyclone 46, I may obtain a final product of a desired particle size. I have found that the particle size tends to increase with an increase of moisture in the sludge delivered by the mixer. This may be simply controlled by the timing of the damper 52 to deliver less of the dry material to the mixer. I have also found that decreasing the speed of drier 24 substantially below present practice tends to enlarge the particles. This may be controlled by adjusting the speed of motor 26. I have further found that decreasing the temperature existing in the cyclone considerably below those presently employed causes the grain size to increase. This may be effected by decreasing the amount of heat delivered to the system by furnace 22. This last measure of control will also lower the degree of drying of the material. Accordingly where an exceptionally large particle size is required resulting in a product that is excessively moist, I may employ a second stage of drying to complete evaporation of moisture.

45 My novel method of drying for controlled particle size may be carried out within the approximate ranges of drying conditions as follows:

50 In usual flash drying the tip speed of the outer rotating bars of drier 24 is about 5000 feet

per minute. When employing my invention this speed normally varies between 2000 feet and 4000 feet per minute.

In usual flash drying, moisture content of the mixture varies between 25% to 35% while I increase the moisture content to between 35% and 50%.

In usual flash drying the temperature existing in the cyclone 48 is about 350 deg. F., while when employing my invention this temperature is reduced to between 200 deg. F. and 350 deg. F.

In drying sewage sludge to produce particles of relatively large size suitable for use as a fertilizer, I have found that very good results are obtained by maintaining a moisture content of 40% in the mixture of raw material and dry return while operating the drier at a peripheral speed of 3200 feet per minute and maintaining a temperature of 300 deg. F. in the cyclone separator.

What I claim is:

1. In the art of drying moisture laden sewage sludge materials in a drying system wherein the material to be dried is carried in a stream of hot gas through a rotary drier of the beater type from which the material and gas pass to a separator, the improved method which comprises; mixing previously dried sludge with the fresh sludge in proportions for maintaining the moisture content of the material to be dried at between 35% to 50%, mixing hot gases with the sludge before admitting the mixture to the drier, operating the drier at a peripheral speed of between 2000 to 4000 feet per minute for the tips

of the drier beaters, and maintaining a temperature of between 200 deg. F. to 350 deg. F. in the separator.

5 2. In the art of drying moisture laden sewage sludge materials in a drying system wherein the material to be dried is carried in a stream of hot gas through a rotary drier of the beater type from which the material and gas pass to a separator, the improved method which comprises; mixing previously dried sludge with the fresh sludge in proportions for maintaining the moisture content of the material to be dried at approximately 40%, mixing hot gases with the sludge before admitting the mixture to the drier, operating the drier at a peripheral speed of approximately 3200 feet per minute for the tips of the drier beaters, and maintaining a temperature of 300 deg. F. in the separator.

10 3. In the art of drying sewage sludge having a moisture content of 70 to 85 per cent in a drying system wherein the sludge is carried in a stream of hot gas through a rotary drier of the beater type from which the material and gas pass to a separator, the improved method which comprises; mixing previously dried material with the fresh sludge in proportions to maintain the moisture content of the sludge to be dried approximately 40 per cent, mixing hot gases with the sludge before admitting the mixture to the drier, operating the drier at a peripheral speed of approximately 3200 feet per minute for the tips of the drier beaters, and maintaining a temperature of 300 deg. F. in the separator..

CHARLES W. GORDON.
